UNITED STATES PATENT OFFICE.

JAMES WILLIAM CROOK, OF BURNLEY, ENGLAND.

FASTENER FOR SECURING BRUSHES, BROOMS, HAMMERS, PICKS, MORTISE-JOINTS, OR THE LIKE.

SPECIFICATION forming part of Letters Patent No. 769,388, dated September 6, 1904.

Application filed April 25, 1903. Serial No. 154,362. (No model.)

To all whom it may concern:

Be it known that I, JAMES WILLIAM CROOK, a subject of the King of Great Britain, residing at 10 Hawk street, Burnley, Lancashire, 5 England, have invented certain new and useful Improvements in Fasteners for Securing Brushes, Brooms, Hammers, Picks, Mortise-Joints, or the Like, of which the following is a specification.

10 This invention relates to certain improvements in fasteners for securing the handles of brushes, brooms, or the like to their stocks. I find my invention also applicable for fastening hammers, picks, axes, and all 15 iron tools of a similar description. My invention may likewise be used for securing mallets and mauls, mortise-joints, and other items of a like nature.

In the application of my invention to 20 brushes, brooms, or the like I take a strip of stout metal about two and a half inches long, more or less, and form at one end one or more prongs, which I bend at right angles. At the 25 other end of the metal strip I punch or bore a small hole. The strip is also bent bow shape or formed with a longitudinal depression or indentation. The strip is placed to stand vertically in the usual hole in the stock or head for the reception of the handle, and 30 the prong or prongs at the end of the strip

are pressed against the internal side of the said hole, so that when the handle is also introduced and forced into the said hole it will drive the prongs home, being assisted in doing so by the pressure it exerts as it is being

driven in against the raised portion of the vertical face of the strip formed by the longitudinal depression on its opposite face. To prevent displacement, a small thumb-screw is now 35 screwed in the hole at the other end of the strip to secure the same firmly to the handle and hold both securely in place, or an ordinary screw or nail may be employed instead. Though I prefer the pronged strip to be made

40 out of one piece of sheet metal, the securing prongs, pins, or spikes may be made separately and fixed by riveting or like means.

In describing the invention in detail ref-

erence is had to the accompanying drawings, forming a part of this application, and in 50 which—

Figure 1 is a perspective view of the improved fastener, and Fig. 2 is a sectional elevation of the brush-stock having a handle secured therein by means of the fastener. 55

As shown in Fig. 1, I take a stout strip of metal 1 and form at one of its ends prongs 2, which are preferably bent at right angles, while at its other end I punch or bore the hole 3. As will be explained later, I make a 60 longitudinal indentation or depression or fluting 13 to assist in driving home the prongs, and I employ the screw 4 for securing the fastener in position. As shown in Fig. 2, 1 is the fastener; 2, the prongs at its end, which 65 are bent preferably at right angles. 13 is the said longitudinal depression or indentation. The fastener is first placed vertically in the hole of the stock and prongs 2 pressed against the internal side of such hole, and 70 when handle 5 is driven in it will drive the prongs home and will be assisted in doing so by the raised portion of the strip formed by the longitudinal depression on its opposite face. Screw 4 is now inserted in the hole 3 75 of fastener (see Fig. 1) and screwed tightly in handle 5, when the brush becomes firmly fixed.

Having now particularly described and ascertained the nature of my said invention and 80 in what manner the same is to be performed, I declare that what I claim is—

1. A fastener for handles consisting of a strip of suitable material having one end bent at right angles and at its other end provided 85 with an opening, said strip having in one of its faces, an indentation extending in the direction of the length of the strip thereby forming the other face of the strip with a projection extending in the same direction as 90 the indentation.

2. A fastener for brushes consisting of a strip of suitable material having one end provided with a prong and one of its faces with a projection extending in the direction 95 of the length of the strip.

3. A fastener for brushes consisting of a strip of suitable material having one end provided with a prong and one of its faces with a projection extending in the direction of the length of the strip, said projection arranged intermediate the longitudinal edges of the strip.

In testimony whereof I have hereunto set my hand in presence of two subscribing witnesses.

JAMES WILLIAM CROOK.
